INVENTOR:

Erich Bernhard Peterson

By Chas. A. Luther
ATTORNEY.

UNITED STATES PATENT OFFICE.

ERICK BERNHARD PETERSON, OF PROVIDENCE, RHODE ISLAND, ASSIGNOR TO GEORGE W. DOVER, INCORPORATED, OF PROVIDENCE, RHODE ISLAND, A CORPORATION OF RHODE ISLAND.

BALL SAFETY-CATCH FOR BROOCHES AND ARTICLES OF A SIMILAR NATURE.

1,328,965.

Specification of Letters Patent.

Patented Jan. 27, 1920.

Application filed July 8, 1919. Serial No. 309,281.

To all whom it may concern:

Be it known that I, ERICK BERNHARD PETERSON, a subject of Sweden, residing at Providence, in the county of Providence and 5 State of Rhode Island, have invented a new and useful Improvement in Ball Safety-Catches for Brooches and Articles of a Similar Nature, of which the following is a specification.

10 My invention has reference to an improvement in articles of jewelry and more particularly to an improvement in safety catches for brooches and the like.

The object of my invention is to improve 15 the construction of safety catches for brooches, pins, and the like, whereby the construction of the catch is in the nature of a ball and socket joint, the construction simplified and strengthened, liability of solder 20 entering the catch, in soldering the catch to a brooch practically eliminated, and the appearance of the catch greatly improved.

My invention consists in the peculiar and 25 novel construction of a ball safety catch for brooches and similar articles of jewelry, said ball safety catch having details of construction, as will be more fully set forth herein-after and claimed.

Figure 1 is an end view of a brooch provided with my improved ball safety catch, showing the catch in the open position in full lines and in the closed position in broken lines.

Fig. 2 is a longitudinal sectional view 35 taken on line 2.2 of Fig. 1 with the catch closed.

Fig. 3 is a top view of the catch in the open position.

Fig. 4 is a transverse sectional view taken 40 on line 4.4 of Fig. 1 with the catch open.

Fig. 5 is an inner face view of the keeper blank or partly formed up keeper.

Fig. 6 is a side view of the ball locking member, and

45 Fig. 7 is an edge view of the ball locking member.

All of the figures in the drawing are greatly enlarged to more clearly show my invention.

50 In the drawing 1 indicates the body of a brooch or similar article of jewelry, 2 a pin-tongue and 3 my improved ball safety catch

which consists essentially of a relatively stationary hollow globular keeper 4 and a movable solid spherical locking member 5.

55

The keeper 4 is in the form of a hollow globular body 6 having oppositely disposed radial pin-tongue openings 7. 7 which extend from the center outward, oppositely disposed radial slots 8. 8 at right angles to the pin-tongue openings 7. 7 and which extend from the center outward, and a closed cuffed base 9 which raises the body 6 a predetermined distance above the back of the brooch and in the bottom of which is a 60 groove 10 corresponding to the slots 8. 8 and which forms practically a continuation of the slots 8. 8 in the keeper.

The locking member 5 is in the form of a solid spherical body 11 having a pin-tongue 70 opening 12 which extends radially from the center outward, and a central annular rib 13 which merges outward into a short operating member 14. The spherical body 11 has a movable fit in the hollow globular 75 keeper 4, it is held in place and guided by the rib 13 in the slots 8. 8 and the groove 10 in the bottom of the keeper, and the operating member 14 extending out through a slot 8 in the keeper. The locking member is secured in the keeper by placing the locking member on the blank or partly formed keeper and then, by the use of suitable dies, forming the upper portion of the hollow globular body of the keeper around the 80 solid spherical body of the locking member 5.

When in use the pin-tongue is locked in the catch by depressing the pin-tongue into the pin-tongue openings 7. 7 in the keeper and pin-tongue opening 12 in the locking 90 member. The locking member is now given one-half of a revolution in the keeper, by the operating member 14, as shown in broken lines in Fig. 1.

By the use of my improved construction, 95 safety catches, which are necessarily small and heretofore weak in construction, are given the strongest possible construction, as the upper portions of the hollow globular keeper, when formed over the spherical body 100 of the locking member, forms curved rigid arms over the locking member, which positively secures the locking member in the keeper.

It is evident that my improved ball safety catch could be varied in details of construction within the scope of the appended claim.

Having thus described my invention I claim as new:—

10 A ball safety catch for brooches and the like comprising a hollow globular keeper having oppositely disposed radial pin-tongue openings, oppositely disposed radial slots and a raised closed base in the bottom of which is a groove forming practically a continuation of the radial slots, a solid spherical locking member in the hollow

globular keeper and having a radial pin-tongue opening, coinciding with the radial 15 pin-tongue opening in the keeper when the catch is open, and an annular rib in and guided by the slots and groove in the keeper, the rib merging into an operating member which extends out through a slot in the 20 keeper, and means for securing the locking member in the keeper, as shown and described.

In testimony whereof, I have signed my name to this specification.

ERICK BERNHARD PETERSON.
